(57) **CLAIM**

We claim the ornamental design for ink tank for micro-fluid applications, as shown and described.

DESCRIPTION

FIG. 1 is a perspective view of an ink tank for micro-fluid applications;

FIG. 2 is a top view of the ink tank for micro-fluid applications;

FIG. 3 is a bottom view of the ink tank for micro-fluid applications;

FIG. 4 is a rear view of the ink tank for micro-fluid applications;

FIG. 5 is a front view of the ink tank for micro-fluid applications;

FIG. 6 is a left side view of the ink tank for micro-fluid applications; and,

FIG. 7 is a right side view of the ink tank for micro-fluid applications.

The broken lines are for illustration only and form no part of the claimed design.
